UNITED STATES PATENT OFFICE.

MORRIS HENSCHEL, OF NEW YORK, N. Y.

SCARF.

SPECIFICATION forming part of Letters Patent No. 373,933, dated November 29, 1887.

Application filed December 27, 1886. Serial No. 222,581. (No model.)

To all whom it may concern:

Be it known that I, MORRIS HENSCHEL, of the city, county, and State of New York, have invented certain new and useful Improvements in Scarfs, of which the following is a specification.

This invention relates to an improvement in the scarf for which Letters Patent were granted to me, No. 208,093, dated September 17, 1878, the improvement being designed to adapt said scarf to the so-called "tie" or knotted scarfs in general use; and the invention consists of a scarf having a head or knot provided with a rigid center piece or partition, and with a raised bridge or cross-bar projecting above the head, body-pieces attached to said head, and an adjustable center piece formed of a flexible middle portion and tapering ends that are passed over the cross-bar and downward at both sides of the partition. The neckband is attached at one end to the partition, while the free end is passed through between the same and the adjustable center piece.

In the accompanying drawings, Figure 1 represents a front elevation of my improved scarf; Fig. 2, a rear elevation; Fig. 3, a vertical transverse section of the same; Fig. 4, a detail plan view of the adjustable center piece, shown as detached from the scarf; and Fig. 5 is a top view of my improved scarf.

Similar letters of reference indicate corresponding parts.

Referring to the drawings, A represents the head or knot of my improved scarf, and B the body-pieces of same, which are attached in the usual manner to the front part of the head or knot A.

The head A is provided with a rigid center piece or partition, B', which is made of pasteboard, sheet metal, or other stiff material, that is extended above the upper edge of the head A, so as to form a raised or projecting bridge or cross-bar, b, as shown in dotted lines in Fig. 1; or said raised bridge or cross-bar b may be made of a metal strip, that is stitched or otherwise securely fastened to the partition B'.

The neckband C is attached at one end to the partition B', while its other or free end is

ready to be passed through the head A at either side of the partition. An adjustable center piece, D, of the shape shown in Fig. 4, is provided with a middle wider and flexible part, d, corresponding to the width of the head A, and narrow tapering ends d' d'. These ends are passed through the head A of the scarf at both sides of the partition B' until the middle portion, d, is stopped by the raised bridge b. (Shown in Figs. 1 and 2.) Before the center piece, D, is entirely folded down the free end of the neckband C is inserted between the doubled-up center piece, D, and the partition and placed in position on the locking-pin of the head, as shown in Fig. 2, upon which the center piece, D, is moved by taking hold of its lower ends, so that it tightly binds on the free end of the neckband, and imparts thereby to the neckband the appearance of a tied or knotted scarf, as shown in Fig. 1.

When the scarf is removed from the neck, the center piece is first lifted by pushing its ends upward, so that the free end of the neckband can be readily removed.

The adjustable center piece can be used on both sides, as it is covered on both sides, it being thereby more durable and adapted to be worn longer, so as to be worn as long as the body of the scarf lasts.

By applying a shield and elastic to the rear part of the head or knot A the neckband may be dispensed with, and the scarf worn with a turned-down collar.

Having thus described my invention, I claim as new and desire to secure by Letters Patent—

1. The combination, in a scarf, of a head or knot having a rigid center piece or partition, and a bridge or cross-bar projecting above the head, body-pieces attached to said head or knot, a neckband attached at one end to said partition, and an adjustable reversible center piece formed of a flexible middle portion and tapering ends, said center piece being doubled up over the bridge and passed through the head at both sides of the partition, substantially as set forth.

2. The combination, in a scarf, of a head or knot having a rigid center piece or partition, with a bridge or cross-bar projecting above

the head or knot, body-pieces attached to said head or knot, and an adjustable and reversible center piece formed of a flexible middle portion and tapering ends, said center piece being doubled up over the bridge and passed through at both sides of the partition, substantially as set forth.

In testimony that I claim the foregoing as my invention I have signed my name in presence of two subscribing witnesses.

MORRIS HENSCHEL.
